(57) CLAIM

The ornamental design for a massage tool, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, upper, left perspective view of a massage tool of our new design;

FIG. 2 is a rear, lower, right perspective view thereof;

FIG. 3 is a top view thereof;

FIG. 4 is a bottom view thereof;

FIG. 5 is a right view thereof;

FIG. 6 is a left view thereof;

FIG. 7 is a front view thereof; and,

FIG. 8 is a rear view thereof.

Broken lines represent unclaimed subject matter and form no part of the claimed design. No particular color is claimed.
